(57) CLAIM

The ornamental design for dresser mirror, as shown and described.

DESCRIPTION

FIG. 1 is a front elevational view of a dresser mirror showing my new design;

FIG. 2 is right-side elevational view thereof;

FIG. 3 is left-side elevational view thereof;

FIG. 4 is a top plan view thereof; and,

FIG. 5 is an elevational detail of the center arch portion of the dresser mirror illustrating the ornamentation thereon in enlarged detail.

The claimed design does not include any depth for the ornamental details shown within the perimeter moldings.
